UNITED STATES PATENT OFFICE

NORMAN WALKER AND CHARLES H. LAKE, OF LOCKPORT, NEW YORK, ASSIGNEES TO
GENERAL MOTORS CORPORATION, OF DETROIT, MICHIGAN, A CORPORATION OF
DELAWARE

RADIATOR DUMMY CORE

Application filed November 5, 1928. Serial No. 317,416.

This invention relates to radiators and has particular reference to the radiators used on automotive vehicles.

Modern radiators on automotive vehicles are extended well down between the side bars of the chassis frame, to improve the vehicle's appearance and to obtain the effect of depth to the radiator and although this depth is desirable from an appearance standpoint, it is nevertheless not necessary to increase the size of the radiator. It is therefore now common practice to use a dummy core below the regular radiator core. This will give the effect desired and at the same time cheapen the construction for the reason that the dummy core is much cheaper to construct and as it per se forms no part of the actual cooling system, an injury thereto will in no way affect the radiator system.

The invention is concerned with the construction of the dummy radiator which is placed beneath the radiator core of the engine. The core is constructed by taking a sheet of flat metal and placing therein a plurality of symmetrically and staggeredly arranged cuts or slits and then bending the sheet transversely of and at the ends of the cuts into a plurality of substantially U-shaped continuous formations. The sheet is then again bent at right angles to the first bend and along the line of each series of cuts. In this second bending operation the sheet is bent back entirely upon itself and in its final form is honeycomb in shape and will give a honeycomb effect, in all respects similar to the honeycomb of the usual radiator.

Behind the dummy radiator core there is mounted or positioned a plate having a plurality of indentations which are polygonal or diamond shaped. These indentations are preferably suitably painted and one indentation appears behind each opening in the dummy honeycomb core. This will give a lighting effect as the rays from an oncoming vehicle strike the indentations in the rear plate. The painted indentations form a reflecting surface and the plate may therefore be termed a reflecting plate.

Referring to the drawings:

Fig. 1 shows the lower portion of the ra-

diator of an automotive vehicle with the dummy core shown.

Fig. 2 is an enlarged detail view of a portion of the dummy core.

Fig. 3 is a section through Fig. 2. 55

Fig. 4 is an enlarged detail view of a portion of the dummy core.

Fig. 5 is a view of the flat sheet used to form the dummy core and showing the symmetrically and staggeredly arranged slits or 60 cuts.

Figs. 6 and 7 are sections on the lines 6—6 and 7—7 of Fig. 5.

Fig. 8 is a view of the plate in Fig. 5 but showing the plate bent along the lines of the 65 ends of each series of cuts.

Fig. 9 is a section on the line 9—9 of Fig. 8 and showing in side view the U-shaped formation of the bends.

Fig. 10 is a section on the line 10—10 of 70 Fig. 8 and showing the plurality of continuous substantially U-shaped bends or formations.

Figs. 11 and 14 are views of successive 75 steps in the formation of the core, the bending operation being continued at right angles to the first and along the lines of the cuts.

Figs. 12 and 13 are sections along the lines 12—12 and 13—13 of Fig. 11.

Figs. 15 and 16 are sections along the lines 80 15—15 and 16—16 of Fig. 14.

Fig. 17 is a view of the core after the bending operations have been completed.

Figs. 18 and 19 are respective sections on 85 the lines 18—18 and 19—19 of Fig. 17.

Referring to the drawings the numeral 2 indicates the conventional honeycomb radiator of an automotive vehicle, 4 the radiator shell, 6 the dummy core and 8' the cap covering the end of the crank shaft. At the rear of the dummy core 6 there is placed or mounted the reflecting plate 8 having the upper and lower flanges 10 and 12 respectively, and lateral flanges, not shown. The upper flange 10 90 serves as a dividing or finishing strip between the two cores. The core 6 is secured in the reflecting plate in any suitable way and the plate in turn secured to the shell by means of the welded or riveted brackets 14 95 100

and securing means 16 passing through brackets and flanges.

The invention is particularly concerned with the construction of the dummy core 5 which is shown in detail in Figs. 5 to 19, inclusive.

Referring to Figs. 5 to 7 inclusive, use is made of a flat sheet 18 which is provided with a plurality of symmetrically and staggeredly arranged cuts or slits 20 as shown in Fig. 5. After the sheet has been provided with the cuts 20 it is bent by a suitable tool or in a suitable machine along a line following the ends of each set of cuts 21 as shown in Fig. 8. The final form of the plate after it has received its first bending operation is shown in Figs. 8, 9 and 10, as is better seen in Fig. 10. The original flat plate now assumes a plurality of continuous substantially 20 U-shaped formations indicated at 22.

The sheet is now given its second operation and is bent upon itself through substantially 180 degrees, successive steps in the bending being shown in Figs. 11 to 16 inclusive. The 25 sheet is bent in alternate directions as shown at 24 and 26, the folding being along the longitudinal line of the cuts. When the core is finally folded it will appear as shown in Figs. 4 and 17 to 19 inclusive.

30 From an examination of the enlarged view of the final form in Fig. 4, it will be noted that the adjacent U-shaped formations of Fig. 9 have been bent into overlapping relation to form the honeycomb opening 28. The 35 various honeycomb portions are held together by means of the uncut and bent over portions 30 conforming to the bends at 24 and 26 and representing the portion of the flat sheet between adjacent ends of the aligned 40 cuts 20.

The reflecting plate 8 is indented or punched by a suitable tool to provide a plurality of indentations 32 which are polygonal or diamond shaped, as best shown in Fig. 2. 45 These indentations are so arranged that one will appear behind each opening 28 in the dummy core 6, as is best shown at the upper left hand corner of Fig. 2. The indentations are given a coating of a suitable paint and as the light from an oncoming vehicle strikes 50 the indentations it will be reflected and lend visibility to the dummy core.

I claim:

55 1. In a dummy core construction for radiators, a plate behind said construction, said plate having a plurality of indentations therein.

60 2. In a dummy honeycomb core construction for radiators, a plate behind said construction, said plate having a plurality of indentations therein, one indentation behind each honeycomb opening.

65 3. In a dummy core construction for radiators, a plate at the rear of said core construction, flanges on said plate embracing the core

construction sides, said plate having a plurality of indentations therein.

4. In a dummy radiator construction, a dummy core, and a light reflecting plate mounted in the rear of said core. 70

5. In a radiator construction, a dummy core, a plate mounted in the rear of said core, said plate having a plurality of light reflecting indentations therein.

6. In a radiator construction, a dummy 75 honeycomb core, a plate mounted to extend over the rear of said core, said plate having a plurality of light reflecting indentations therein, one indentation at the rear of each honeycomb opening. 80

7. In a dummy honeycomb core construction for radiators, a plate behind said construction, said plate having a plurality of polygonal indentations therein adjacent said core construction, one indentation behind 85 each honeycomb opening.

8. In a dummy honeycomb core construction for radiators, a plate at the rear of said core construction, flanges on said plate embracing the core construction sides, said plate 90 having a plurality of polygonal indentations therein immediately behind the core.

In testimony whereof we affix our signatures.

NORMAN WALKER. 95
CHARLES H. LAKE.
